SHADE MOUNTING

Stanley J. Blasco, Erie, Pa.

Application July 12, 1944, Serial No. 544,508

2 Claims. (Cl. 248—272)

This invention relates to new and useful improvements in mountings for window shade rollers.

The principal object of the present invention is to provide a roller mounting of the character described which can be constructed of plastic or some other readily available and inexpensive material.

Another important object of the invention is to provide an adjustable shade mounting which can be readily adjusted to accommodate shade rollers of various lengths.

Other important objects and advantages of the invention will become apparent to the reader of the following description.

In the drawing:

Figure 1 is a fragmentary sectional view showing the mountings and a shade roller in top plan.

Figure 2 is a front elevational view of the face member of the mounting.

Figure 3 is an end elevational view of one of the mountings.

Figure 4 is an elevational view of the slide.

Figure 5 is an elevational view of the slide.

Referring to the drawing wherein like numerals designate like parts, it can be seen that reference character A denotes a window frame to which the improved mountings generally referred to by numeral 5 are attached.

Each mounting consists of a base plate 6, preferably constructed of some plastic material and having a dovetail slideway 7 formed therein. The plate has its back wall formed with end openings 8, 8 to accommodate attaching screws 9 and a plurality of longitudinally spaced recesses 10a for receiving selectively the adjacent end of a pin 10 which is slidably disposed through a slide block 11, this slide block having a flared and dovetailed portion 12 disposed in the dovetail slideway 7.

The outer portion of the block 11 has a right angularly cut out portion 13 receiving a substantially rectangular shaped knob 14, there being a tongue and groove connection 15 between the knob 14 and the narrow protruding portion 16 defined by the cut-out 13.

In the protruding portion 16 is a recess 17 for receiving the corresponding end pintle of a shade roll 18.

As can be clearly seen in Figure 1, the outer

end of the pin 10 is threaded into the knob 14 as at 19 and a coiled compression spring in the block 11 serves to project the pin 10 into one of the recesses 10a.

It can now be seen, that with the mounting 5 placed on the window frame or wherever else convenient, the blocks 11 can be adjusted on the base plate 6 to properly accommodate the shade roller. The shade roller can be released at any time desired by simply pulling out on one of the knobs 14 and shifting the corresponding block 11 away from the roller, thus releasing the roller.

While the foregoing specification sets forth the invention in specific terms, it is to be understood that numerous changes in the shape, size and materials may be resorted to without departing from the spirit and scope of the invention as claimed hereinafter.

Having described the invention, what is claimed

20 as new is:

1. The combination of a base plate provided with a series of aligning apertures, a block slidably mounted in the plate and provided with a pintle receiving recess, a horizontal bore extending through the block, a pin slidable within the bore and selectively engageable with one of said series of apertures, said bore being at right angles to said apertures, and being enlarged, a contraction spring in said enlargement engaged with 30 the pin to normally hold the same seated within one of the apertures, and said block having a recess a head secured to said pin adapted to seat within the recess.

2. The combination of a base plate provided with a series of aligning apertures, a block slidably mounted in the plate and provided with a pintle receiving recess, a horizontal bore extending through the block, a pin slidable within the bore and selectively engageable with one of said series 35 of apertures, and said bore being at right angles to said apertures, and being enlarged, a contraction spring in said enlargement engaged with the pin to normally hold the same seated within one of the apertures, said block having a recess and 40 a head secured to said pin and adapted to seat within the recess, and means for guiding said head into its seat.

STANLEY J. BLASCO,
